UNITED STATES PATENT OFFICE

155,459

DESIGN FOR A LAMP CASING OR SIMILAR ARTICLE

Willson Young Stamper, Newark, and Louis Z. La Forest, Parsippany-Troy Hills Township, Morris County, N. J., assignors to Thomas A. Edison, Incorporated, West Orange, N. J., a corporation of New Jersey

Application July 13, 1949, Serial No. 3,874

Term of patent 14 years

(Cl. D48—24)

To all whom it may concern:

Be it known that we, Willson Y. Stamper, a citizen of the United States and a resident of the City of Newark, county of Essex, and State of New Jersey, and Louis Z. La Forest, a citizen of the United States and a resident of Parsippany-Troy Hills Township, county of Morris, and State of New Jersey, have invented a new, original, and ornamental Design for a Lamp Casing or Similar Article, of which the following is a specification, reference being had to the accompanying drawing, forming a part thereof.

In the drawing:

We claim:

The ornamental design for a lamp casing or similar article, substantially as shown.

WILLSON Y. STAMPER.
LOUIS Z. LA FOREST.
